UNITED STATES PATENT OFFICE.

JOHN W. MACKENZIE, OF SAN FRANCISCO, CALIFORNIA.

APPARATUS FOR FREEING SHIPS' HOLDS FROM WATER.

Specification of Letters Patent No. 27,138, dated February 14, 1860.

To all whom it may concern:

Be it known that I, JOHN W. MACKENZIE, of San Francisco, in the county of San Francisco and State of California, have invented 5 a new and useful Improvement in Raising or Discharging Water Out of Ships' Holds; and I do hereby declare that the following is a full, clear, and exact description of the same, reference being had to the accompanying drawings, forming a part of this specification, in which—

Figure 1, is a partial side elevation and partial section of a ship with my improvements applied to it. Fig. 2, is a partial plan 15 and partial horizontal section of the same, and Fig. 3, is a transverse section of the same in the line y, y .

Similar letters of reference, in each of the several figures indicate corresponding parts. 20 The nature of my invention consists in the arrangement of certain chambers and valves in such relation to and in communication with a ship's hold, and discharge passages that as the ship pitches fore and aft 25 or rolls heavily any water which flows into her hold by reason of leaks being sprung shall be automatically raised therefrom and discharged into the sea, and thus loss of life and cargo and ship avoided or prevented 30 until succor arrives.

To enable others skilled in the art, to make and use my invention, I will proceed to describe its construction and operation.

In applying my invention I either select 35 the stern, bow or sides of the ship's hold as a place of location.

In the accompanying drawings, A, represents a ship's hold. At the stern of the same is constructed a separate chamber B, which 40 is divided horizontally into a series of compartments $a, a^1, a^2, a^3, a^4, a^5$. The partitions d, d, d, d , forming these compartments are alternately placed horizontal and inclined. The first or lowest compartment a , 45 communicates with the ship's hold by means of a series of passages b, b , which are covered with flap valves opening into the chamber B, while the last or uppermost compartment a^5 , empties into the sea by means of passages 50 c, c , which may be closed with outwardly opening flap valves. The partition of the compartment a , inclines downward slightly from the stern of the hold to the stern of the chamber B, and is furnished with a flap 55 valve f , which opens upward near the stern

of the chamber B. The partition d^1 , runs horizontally and also has a flap valve f^1 , which opens upward, near the stern of chamber B. The partition d^2 inclines downward from the stern of chamber B, and terminates on and near the front end of the partition d^1 . It also has a flap valve f^2 near its front end; said valve opening upward, but in a reverse direction to that in which f^1 , opens. The partition d^3 , is horizontal and 60 is furnished with an upwardly opening valve f^3 at its stern end. The partition d^4 , is inclined and arranged and furnished with a valve f^4 , in precisely the same manner as the partition d^2 . The partition d^5 , is horizontal and 65 forms the top to the chamber a^5 .

The several partitions with the aid of parts of the ship or independent side and end plates or boards form separate closed compartments, as represented. Each of 70 which can be inspected and have its valves adjusted by simply turning up the partitions and their attachments on the hinge joints g, g .

From the above description of parts, it 75 will be seen that if the ship is pitching fore and aft heavily and water is running into her hold there will be no necessity for pumps being put into action, for as fast as the water runs in, it will be discharged at each 80 downward aft pitch of the ship, into the lower compartment a , of the chamber B, through the valved passages b, b , and from said compartment into the compartments a^1, a^2 . The first quantity which leaked into the 85 hold having been discharged into the compartments a, a^1, a^2 , will as the ship makes a downward fore pitch, be caused to rush out of these compartments into the compartment a^3 , and when the ship makes another 90 downward aft pitch the water which leaked into her hold while she was pitching forward will be discharged into the compartments a, a^1, a^2 , and consequently, and also 95 by reason of the aft pitch, the water which remained in the compartments a, a^1, a^2, a^3 , will be compelled to pass into the compartments a^4, a^5 , and from thence through the 100 passages c, c , into the sea. The discharge of 105 the water from one compartment into another at the fore and aft pitchings of the ship, and the retention of the water in the compartment in which it was last discharged being accomplished by the alternate inclination of the partitions and the reverse set of 110

the valves in the manner described and represented in the drawings. The same result will be attained if the arrangement of valued compartments be located at one or both sides 5 of the ship or at the bow of the same.

What I claim as my invention and desire to secure by Letters Patent, is—

The arrangement of compartments a , a^1 , 10 a^2 , a^3 , a^4 , a^5 , and valves f , f^1 &c. in relation to and in communication with a ship's hold

A, and discharge passages c , constructed as and for the purposes described.

The above specification of my improved method of raising water out of ship's holds, signed by me this 31st day of December, 15 1859.

J. W. MACKENZIE.
